(57) **CLAIM**

We claim the ornamental design for a remote control, as shown and described.

DESCRIPTION

FIG. 1 is a perspective view of a remote control showing our new design;

FIG. 2 is a plan view thereof from above;

FIG. 3 is a bottom view thereof;

FIG. 4 is a front view thereof;

FIG. 5 is a rear view thereof;

FIG. 6 is a side view thereof; and,

FIG. 7 is a view of the opposite side of FIG. 6.
